O. H. LE COMPTE

AUTOMATIC CAR AND TRAIN LINE COUPLING

Filed Feb. 16, 1921

by Oscar A. Michel ATTORNEY

UNITED STATES PATENT OFFICE.

ONESIME H. LE COMPTE, OF ST. LOUIS, MISSOURI, ASSIGNOR TO LE COMPTE STANDARD AUTOMATIC DRAWBAR AND CONNECTOR COMPANY, OF DENVER, COLORADO.

AUTOMATIC CAR AND TRAIN-LINE COUPLING.

Application filed February 16, 1921. Serial No. 445,472.

To all whom it may concern.

Be it known that I, ONESIME H. LE COMPTE, a citizen of the United States, residing at St. Louis and State of Missouri, have invented new and useful Improvements in Automatic Car and Train-Line Couplings, of which the following is a specification, reference being had to the accompanying drawings.

10 My invention relates to improvements in combined automatic car and train line couplings.

15 My primary object is to provide means of simple and inexpensive construction which will operate, with certainty under all ordinary conditions, to automatically couple cars and simultaneously with the coupling of the cars make connections in the train lines, such as steam pipes for heating, air

20 pipes for signal and brake purposes and conductors in electric light circuits.

25 A further object is to construct a coupler of the combined car and train line type in a manner facilitating assemblage, having special regard for reducing the repair and upkeep expenses.

30 A still further object is to construct the car coupling elements and the train line coupling elements as distinct structures and to provide means for their ready relation which latter means includes devices for adjusting the trainline coupling elements with relation to the car coupling elements in order to "set" the former elements in positions

35 to function properly.

40 My improvements consist in the novel construction, arrangement and combination of parts as hereinafter fully, clearly, concisely set forth, definitely pointed out in my claims and illustrated by the accompanying drawings, in which:—

45 Figure 1 is an elevation of two coupled couplings equipped with train line couplings in accordance with my invention.

Figure 2 is a front elevation of one of the car couplings and a train line coupling.

Figure 3 is a perspective of one of the train line manifolds.

50 Figure 4 is an enlarged fragmental longitudinal sectional elevation showing the detail constructure of a train line terminal.

Figure 5 is a perspective view of a modified form of manifold.

Referring by numerals to the drawings, 5 and 6 designate the car coupling heads having the locking pins 7 and 8 and drawbars 9 and 10.

55 The elements, just recited, are of the type illustrated described in a co-pending application filed February 27th, 1920, Serial Number 361,891 but I do not wish to be understood as limiting myself to such car couplers as obviously my train line couplings may be employed with other types of car couplings.

60 As shown each of the car coupling heads 5 and 6 has on its lower face a pair of opposed guides, or hangers, 11 having on their inside faces flanges 12 and at the rear of the guides a transversely disposed rib or stop 13, (as shown by dotted lines in Figure 1,) and carried by each stop 13 there is a set screw 14.

65 The train line coupling comprises a pair of manifolds 15 each having a slide-block 16 from which the manifolds may be suspended from the flanges 12 of the guides 11 and by preference the manifolds and slide-blocks are formed en bloc.

70 Formed through each of the manifolds, lengthwise, there is one or more bores or openings 17, through which are extended nipples 18, externally threaded at each end to receive, at their rear ends, elbows 19, or their equivalents and to receive at their forward ends the nuts 20, which serve with said elbows to fix the nipples against movements in the manifolds, and, the resilient gasket like train line coupling terminals 21. As shown in Figure 4 the terminals may be secured to the nipples by means such as the clips 22.

75 With the elbows 19 connected with the various "lines" of the train, and upon a bringing together of two cars equipped with my couplings it will be obvious that the cars will be coupled and that all train lines will be automatically coupled.

80 By means of the sliding relation between the manifolds and their hanger on the coupling heads and the set screws 14, the manifolds may be adjusted longitudinally of the coupling head whereby the gasket like train line terminals may be properly related to relatively "connect" to establish non-leaking train line connections.

In Figure 5 I show a manifold having a single train line terminal in which the elbow is formed in the block.

What I claim as new is:—

- 5 In a manifold structure, in combination with a pair of opposed guides, a flange directed inwardly from each guide, a stop having a screw threaded opening uniting the rear ends of the guides, a manifold, a 10 slide block extending beyond the side faces and the rear face of said manifold for slidably suspending the manifold from said flanges, a set screw engaging in said screw threaded opening of the stop having its forward end in engagement with the rear extended end of the slide block, longitudinally directed openings formed through the manifold, a nipple having screw threaded ends receivable in each opening with the screw

threaded ends thereof extending beyond the 20 front and rear faces of the manifold, an elbow having screw threaded engagement with the rear end of each nipple, a nut having screw threaded engagement with the 25 forward end of each nipple serving with the elbows to fix the nipples against longitudinal movement, a resilient gasket like train line terminal removably fixed to the forwardly extended ends of each nipple and extending beyond the front edges of each 30 nipple so that the front face of each terminal will lie in a plane with the front face of the coupler when brought into coupled contact with the terminal of a companion coupler. 35

In testimony whereof I hereunto affix my signature.

ONESIME H. LE COMPTE.
